APPARATUS FOR PRODUCING ICE

Hans Tietz, Leverkusen-Wiesdorf, Germany, assignor to I. G. Farbenindustrie Aktiengesellschaft, Frankfort-on-the-Main, Germany

Application December 14, 1934, Serial No. 757,544
In Germany December 16, 1933

10 Claims. (Cl. 62—107)

The present invention relates to a process and apparatus for producing ice by partial evaporation of water in vacuo.

It is known that water is partially converted into ice when subjecting it to a vacuum without supplying heat. Part of the water evaporates and withdraws heat from the remaining part of the water so that it freezes to ice. Various apparatus have been constructed for producing ice in accordance with this process. Up to the present time, however, it has not been possible to obtain ice by this process in a continuous manner of working because the water introduced into the vacuum chamber freezes to one ice bar which can only with the greatest difficulty be taken out of the vacuum chamber and only while interrupting the process.

In accordance with the present invention these difficulties are entirely overcome, and a continuous production of ice is made possible by continuously withdrawing the ice formed in the vacuum chamber by means of an extruding press in which the ice bar formed serves as sealing medium for maintaining the vacuum. For this purpose a guide for the ice bar is provided and this guide is formed with a slight conicity so that the ice bar is pressed against all parts of the guide. Among the various extruding presses the worm extruding press has proved especially suitable since this press comprises the most simple mechanism and is best to be sealed against the high vacuum. In order to prevent heat radiation from the outside it is advisable to arrange the press in the vacuum chamber itself. If the compression part of the press is to be cooled this part of the apparatus is sprayed with water. Because of the vacuum partial evaporation of the water and strong undercooling or freezing of the remainder will take place at this part. The press is thereby cooled without a special cooling chamber being necessary.

For enabling a continuous working of the ice producing apparatus it has proved advantageous to introduce the water into the apparatus in such a manner that it reaches the bottom of the apparatus in the form of ice. The introduction of the water in such a manner that it reaches the bottom of the apparatus in the form of ice can be achieved in various ways. Thus it is possible to spray the water against the walls of the vacuum chamber and to scrape off the ice formed from the walls by a suitable device, or to heat the walls so that the ice falls on to the bottom from where it is withdrawn by a withdrawing device.

According to another feature of the invention it is likewise possible to shake the walls of the apparatus for instance by concussions so that the ice formed on the walls breaks off.

In the case a Laval-expansion nozzle is used as the introducing means for the water by which the ice is obtained in the form of snow it is necessary to heat the walls of this nozzle, for the nozzle would be clogged by ice if the walls of the nozzle would reach a temperature below zero. This heating of the nozzle may be attained in various ways, for instance, electrically, but since only slight heating is required it will be sufficient to heat the walls of the nozzle by means of the water introduced in such a manner that the water is caused to flow through the hollow walls of the nozzle before it enters the vacuum chamber. Thereby also pre-cooling of the water is attained.

In accordance with a preferred feature of the new process the water is introduced into the vacuum chamber in one straight jet, which jet is exposed to vacuum before it touches the walls or bottom of the vacuum chamber for so long that the jet is given ample time to completely freeze under the influence of the withdrawing of heat from its surface by partial evaporation. This can be effected in such a manner that the jet is sprayed in from the bottom to the top so that the time during which the jet is exposed to the vacuum is prolonged by the previous rising time and on the whole amounts to twice the time the drop requires for falling down. Further practice has shown that the jet at its turning point dissolves in single drops so that thereby the cooling and evaporating surface is essentially enlarged, on the one hand, and the form of the drops remains so large that the frozen product takes the form of hail-stones rather than snow, on the other hand, which hail-stones cannot be carried over readily by the steam drawing off.

A still more preferred way to expose the water to the high vacuum as long as possible without touching the walls of the vacuum chamber consists in extending the water in a thin layer over moving surfaces whereon it freezes, and then taking it off in the form of ice. This slowly moving surface may be for instance a drum. Particularly suitable as moving surface has proved a conveyor belt from metal, leather, or still better, rubber. When causing water to trickle over such a belt at the one end and fixing the velocity so that the water is frozen when the direction of the drum or endless band is changed it has been

found that the ice at the turning point separates from the band and moves forward as a flat, thin ice bar without any special mechanical means being necessary. The band may be used horizontally, vertically as well as in any desired oblique direction. In order to prevent water from freezing on the walls of the vacuum chamber caused by splashing from the band it is advisable to combine three or more bands to one closed shaft so that splashes cannot reach the outside of the shaft.

The invention is further illustrated by the accompanying drawings.

In Fig. 1 the numeral 3 indicates a worm extruding press. The worm extruding press 3 is arranged in the vacuum chamber 1. Above the press 3 there is a funnel 4. In order to prevent the ice from falling between the funnel 4 and the wall of the vacuum chamber 1, the wall is provided with a flange 5 overlapping the edge of funnel 4. For cooling the compression part of the press a water-injector 6 is provided. The water which is sprayed upon the compression part in only small quantities freezes under the influence of the vacuum but is continuously transformed into water by the compression heat generated in the press until it has completely evaporated under the influence of the vacuum.

Figures 2 and 3 represent two different devices for obtaining the ice in vacuum. In these devices the water is sprayed through a nozzle 7 on to the walls of the vacuum chamber. In Figure 2 the ice frozen to the walls is scraped off by scrapers 8 which are fastened on a shaft 9, thus the ice falls into the discharging device. In Figure 3 the walls of the vacuum chamber 1 are conically shaped and provided with a heating jacket 10. The water sprayed in first freezes at the walls, since the withdrawal of the heat by partial evaporation in an evacuated chamber proceeds more rapidly than the heat can flow from the heating jacket which is cooled by the water that is sprayed in. With increasing thickness of the ice layer the passage of the heat 45 becomes more and more difficult and by and by the flow of the heat from the heating jacket becomes greater than the flow of the heat through the ice. Therefore, the ice will melt at the wall, the crust will break off from the wall and fall 50 downwards into the discharging device.

Figure 4 illustrates an introduction device for the water wherein the water expands in the nozzle 11, constructed in the form of a Laval-nozzle. In this nozzle the water is transformed into snow which falls into the discharging device. In order to prevent clogging of the nozzle by the formation of ice the nozzle is heated. Heating preferably takes place by means of the introduced water flowing through a water-jacket surrounding 55 the nozzle. The water enters the water-jacket of the nozzle at 12 and at 13 it enters the nozzle and passes into the vacuum chamber.

Figures 5 to 9 illustrate how the ice is produced while avoiding a contact of the water sprayed in with the wall of the vacuum chamber. For this purpose in Fig. 5 the water is sprayed into the vacuum chamber by the nozzle 7 from below to the top. The rising jet is distributed in single drops which freeze under the influence 65 of the vacuum to hail-stones which fall into the worm extruding press working as discharging device.

In Figures 6 to 9 the water introduced through nozzles 7 is extended upon moving surfaces in thin layers. In Fig. 6 the moving surfaces are a

pair of drums 14 moving in opposite directions from which drums the ice is taken off by the scrapers 15. It then falls into the funnel 4 and the worm extruding press 3.

In Figures 7 to 9 the moving surfaces are one or more conveyor belts 16. In Figure 7 the conveyor belt is vertically arranged, in Figure 8 it is arranged horizontally and in Figure 9 an arrangement of three conveyor belts 16 in a closed shaft is shown in cross section.

At the upper part of the shaft in the center there is arranged the water introducing nozzle 7 which distributes the water upon the three conveyor belts. By the closed shaft any splashing of the water on to the walls of the vacuum chamber 1 is avoided as any such water would freeze and thereby cause clogging of the vacuum chamber. It is not necessary to scrape off the ice from the conveyor belts, since the ice falls therefrom at the turning point. In Figures 8 and 9 a worm extruding press is likewise illustrated as the discharging device.

I claim:

1. In an apparatus for producing ice by partial evaporation of water in an evacuated chamber, the arrangement of an extruding press, whose cross-sectional dimension diminishes toward the outlet, for withdrawing the ice formed from the vacuum chamber and simultaneously compressing the same into a solid to seal said outlet while sustaining the vacuum in the chamber.

2. In an apparatus for producing ice by partial evaporation of water in an evacuated chamber, the arrangement of a moving device upon the surface of which the water is exposed to the vacuum until it is frozen and a device for withdrawing the ice formed from the vacuum chamber while sustaining the vacuum.

3. In an apparatus for producing ice by partial evaporation of water in an evacuated chamber, the arrangement of a conveyor belt upon which the water is exposed to the vacuum until it is frozen and a device for withdrawing the ice formed from the vacuum chamber while sustaining the vacuum.

4. In an apparatus for producing ice by partial evaporation of water in an evacuated chamber, the arrangement of a conveyor belt of rubber upon which the water is exposed to the vacuum until it is frozen and a device for withdrawing the ice formed from the vacuum chamber while sustaining the vacuum.

5. In an apparatus for producing ice by partial evaporation of water in an evacuated chamber, the arrangement of a moving device upon the surface of which the water is exposed to the vacuum until it is frozen and an extruding press for withdrawing the ice formed from the vacuum chamber while sustaining the vacuum.

6. In an apparatus for producing ice by partial evaporation of water in an evacuated chamber, the arrangement of a conveyor belt upon which the water is exposed to the vacuum until it is frozen and an extruding press for withdrawing the ice formed from the vacuum chamber while sustaining the vacuum.

7. In an apparatus for producing ice by partial evaporation of water in an evacuated chamber, the arrangement of a conveyor belt of rubber upon which the water is exposed to the vacuum until it is frozen and an extruding press for withdrawing the ice formed from the vacuum chamber while sustaining the vacuum.

8. In an apparatus for producing ice by partial evaporation of water in an evacuated chamber, the arrangement of a moving device upon the surface of which the water is exposed to the vacuum until it is frozen and a worm extruding press for withdrawing the ice formed from the vacuum chamber while sustaining the vacuum.

9. In an apparatus for producing ice by partial evaporation of water in an evacuated chamber, the arrangement of a conveyor belt upon which the water is exposed to the vacuum until

it is frozen and a worm extruding press for withdrawing the ice formed from the vacuum chamber while sustaining the vacuum.

10. In an apparatus for producing ice by partial evaporation of water in an evacuated chamber, the arrangement of a conveyor belt of rubber upon which the water is exposed to the vacuum until it is frozen and a worm extruding press for withdrawing the ice formed from the vacuum chamber while sustaining the vacuum.
